UNITED STATES PATENT OFFICE.

STERLING P. ISBELL, OF UKIAH, CALIFORNIA.

SALT-CELLAR.

No. 874,509.

Specification of Letters Patent.

Patented Dec. 24, 1907.

Application filed March 18, 1907. Serial No. 362,952.

To all whom it may concern:

Be it known that I, STERLING P. ISBELL, a citizen of the United States, residing at Ukiah, in the county of Mendocino and 5 State of California, have invented a new and useful Salt-Cellar, of which the following is a specification.

This invention relates to that class of table articles known as salt shakers or salt cellars, the object of which is to produce a salt shaker consisting of two receptacles, one within the other, and longitudinally movable with relation to each other. The inner receptacle will contain salt and be provided 15 with a perforated closure slidable longitudinally through an opening centrally formed in the cap or outer receptacle, which latter receptacle is of greater length than the inner one, to permit the latter moving within the 20 former.

With this and other objects in view the invention consists in the novel construction, combination and arrangement of parts hereinafter described and pointed out in the 25 claims.

In the accompanying drawings: Figure 1 is a perspective view of the improved salt cellar, and Fig. 2 is a longitudinal vertical sectional view of the same.

30 Similar numeral of reference indicate corresponding parts in all the figures.

Broadly stated, the improved salt shaker consists of two parts, an outer receptacle 1 and an inner receptacle 2, adapted to move 35 longitudinally in the outer receptacle. The inner receptacle 2 is made preferably of glass, porcelain or any other suitable, non-corrosive material and sufficiently strong for the use to which it will be applied. It 40 may be cylindrical, square or of any other form desired and of such height and diameter as will make it a convenient article to handle. The top of the receptacle 2 is flat, as shown at 3, forming a shoulder from 45 which extends upwardly a cylindrical neck 4 on the outside of which is formed a screw thread 5. A cap or closure indicated by 6 is formed with a cylindrical body 7 threaded on its inner side and of a height equal to the 50 length of the neck 4 of the inner receptacle 2. The top 6^a of the cap or closure 6 may be flat, or as shown in the drawings, slightly dome shaped and provided with a number of perforations 6^a through which salt is sifted. The cap or closure 6 is screwed on the neck 4 after the receptacle 2 has been filled 55

until its lower edge bears on the shoulder 3 of the inner receptacle.

The outer receptacle 1 is made by preference, though not necessarily, of metal and 60 has an internal shape similar to and of the same diameter as the outside of the receptacle 2 a sufficient space only, being left between them to enable the inner receptacle to slide freely within the outer one without 65 lost motion or rattling. The exterior of the outer casing 1 may have the same shape as the inside or it may differ therefrom in certain respects and be ornamented to suit the taste by enameling, engraving, relief and intaglio work, or any of the numerous ways known to workers in gold and silver. The height of the outer receptacle 1 is a little greater than that of the inner receptacle 2, a 70 space 8 being left between the shoulder 3 and the top of the receptacle 1. A cap 9 is 75 screwed on the upper end of the outer receptacle 1 and has a central opening 10 formed therein, through which the body 7 of the closure 6 extends. As thus constructed, a 80 sufficient quantity of salt having been placed in the inner receptacle 2 and the cap 6 screwed on the neck 4, the said receptacle is placed within the other receptacle or case 1 and the cap 9 slipped over the closure 6 and 85 screwed in place on the upper end of the case 1; the shaker is now ready to be used. The case 1 is grasped in the hand and reversed and on being shaken up and down in the usual manner the inner receptacle or salt 90 holder will slide from one end of the case to the other, causing the salt to be shaken out through the perforations 6^a whenever the shoulder 3 strikes the cap 9.

To reduce the shock of the salt receptacle 95 striking the bottom of the case at one end and the top 9 at the other cushions 11, 12 preferably of rubber are attached to the bottom and cap respectively of the case 1. Besides reducing the shock, the cushions prevent the salt holders from being broken when 100 made of glass or porcelain and silence the noise produced when the two parts come together.

Another great advantage in having the inner receptacle movable longitudinally within the outer one is that the shocks received by the inner receptacle when its movement is arrested is sufficient to keep the salt in the shaker in a constantly loosened condition, 105 prevent it from caking on the sides and ends and insuring a full delivery of salt in the 110

dampest weather. The great objection to salt shakers now in use is the readiness with which salt adheres and hardens on the sides and bottom, and fills the perforations in the 5 cover in damp weather; but with the shaker hereinabove described, the jolting of the salt holder keeps the salt from becoming compacted and shakes out a portion of salt each time the shoulders on the inner receptacle 10 strike the cap on the outer casing.

Having thus described the invention what is claimed is:—

1. A salt shaker comprising an exterior receptacle, an interior receptacle for holding 15 salt shorter than the exterior receptacle and adapted to move endwise therein when shaken in an axial direction and strike against the top and bottom, a closure on the open end of the exterior receptacle having an 20 opening for the neck of the interior receptacle, and a perforated cap closing the neck of the interior receptacle.

2. A salt shaker comprising an exterior receptacle, and an interior receptacle for holding 25 salt shorter than the exterior receptacle

and adapted to move freely therein in an endwise direction when shaken axially and strike with a blow the top and bottom of said exterior receptacle, and cushions between the striking faces at both ends of the receptacles.

3. A salt shaker comprising an exterior receptacle closed at one end, a cap for the open end having an opening, a shorter interior receptacle for holding salt movable freely end- 30 wise within said exterior receptacle and having a neck projecting through the opening in the cap thereof, an end perforated closure for the neck of the interior receptacle, and cushions at each end of said exterior receptacle to break the force of the blow of the inner receptacle.

In testimony that I claim the foregoing as my own, I have hereto affixed my signature in the presence of two witnesses.

STERLING P. ISBELL.
